F. E. WERTHEIM ET AL.

FURNACE DOOR

Filed Dec. 21, 1922

Inventor:

Ferd Eliel Wertheim
Ashur Uri Wetherbee

By

UNITED STATES PATENT OFFICE.

FERD ELIEL WERTHEIM, OF CHICAGO, AND ASHUR URL WETHERBEE, OF EVANSTON, ILLINOIS, ASSIGNORS TO WILLIAM A. GILCHRIST, OF NEW YORK, N. Y.

FURNACE DOOR.

Application filed December 21, 1922. Serial No. 608,332.

To all whom it may concern:

Be it known that we, FERD ELIEL WERTHEIM and ASHUR URL WETHERBEE, citizens of the United States, and residents of Chicago and Evanston, respectively, county of Cook, and State of Illinois, have invented certain new and useful Improvements in Furnace Doors, of which the following is a specification, and which are illustrated in the accompanying drawings, forming a part thereof.

This invention relates to furnaces and has for its object broadly, to provide a door that will effectually close the furnace and can be easily and quickly opened and closed.

More specifically, it is an object of the invention to loosely mount the door on the furnace and provide quick acting wedging devices for forcing it tightly against the door frame. Further objects and advantages of the invention will become apparent as the description is read in connection with the accompanying drawings illustrating a selected embodiment of the invention and in which

Fig. 1 is a front view of the door and door frame, showing the door closed and the wedging devices in operative position; Fig. 2 is an end elevation looking from the right in Fig. 1;

Figs. 3 and 4 are sectional views taken on the lines 3—3 and 4—4 of Fig. 1; and

Fig. 5 is a perspective view of the bushing for adjusting one of the wedging devices.

Referring to the drawings, 10 indicates a door frame, preferably of angular cross section, to provide a flange 11 adapted to be set in the furnace wall, and a flange 12 adapted to rest against the face of the furnace wall. At one side of the door frame the flange 12 is equipped with hinge lugs 14 and 15, adapted to support an intermediate hinge leaf or member 16 having hinge lugs 17 and 18 resting upon the lugs 14 and 15 and pivoted thereto by a pin 19. The door 20 is equipped with a hinge lug 21, resting on top of the intermediate hinge member 16, and a similar lug 22 seated in a notch 23 in the hinge member 16, and a pin 24 pivots the door to the intermediate hinge member. The opposite side of the door frame 10 is equipped with a catch 25, adapted to receive a latch 26 on the door. A handle 27 of any suitable kind is

provided to facilitate the swinging of the door about its hinged mounting.

The door frame opposite to the hinged edge of the door is equipped with a boss 28, in which is mounted a pivot pin 29 on which is a swinging clamping head 30, carrying a wedging device here shown as a screw 31, equipped with handles 32 and adapted to bear against the edge 33 of the door and force it tightly against the face of the door frame. The boss 30 is preferably provided with ribs 35 and 36 adapted to cooperate with the lug 37 on the head 30, to limit its clock-wise motion towards inoperative position, and its counter clock-wise motion towards operative position.

Between the hinge lugs 14 and 17, the hinge pin 19 is equipped with spacing bushings 38 and 39, and between these bushings is pivoted a wedging device in the form of a lever having a long arm 40 adapted to serve as a handle, and a short arm 41 adapted to have wedging engagement with the hinged edge of the door 12. As shown, this edge of the door is provided with an arm 42, reinforced by webs 43, and provided with a bearing surface 44 adapted to cooperate with an eccentric surface 45 on the arm 41.

In order to permit an adjustment of this wedging device, the lever is provided with an eccentric bushing 46, having a head 47 provided with flat faces to receive the wrench by which the bushing may be rotated to increase or decrease the effective length of the wedging arm 41. A screw 48, threaded through the lever, serves to hold the bushing in an adjusted position.

Preferably the door frame is equipped with a groove 49, which, together with the face 50 of the door, forms a pocket surrounding the joint between the door and the door frame to receive clay, asbestos or other packing 51, by which the joint is made gas-tight. The meeting faces 52 and 53 of the door and the door frame, may be machined or otherwise surfaced to make a very close joint.

By thus loosely mounting the door on the furnace, and providing powerful wedging devices to force it into intimate and tight engagement with the door frame, the door is made to effectually close the furnace opening, and by the addition of the packing 51 the joint is made absolutely gas-tight. The

wedging device, including the head 30 and the screw 31, can be quickly thrown into operative position and set up by the powerful leverage afforded by the arms 32 and the pitch of the screw. At the same time it can be quickly released and thrown into inoperative position, out of the way of the door. The opposite edge of the door can be wedged tightly against the door frame by merely swinging the handle 40 to the left, and it is released by merely swinging the handle to the right. When, due to wear, or, in the original set-up the action of the short arm 41 of the lever, is insufficient, the bushing 48 can be rotated by means of a wrench or the like to give the arm 41 the necessary throw.

We claim as our invention:

1. In a furnace, the combination of a door frame, a door loosely mounted on the frame, and means for forcing the door tightly against the frame, including a lever pivoted on the frame and having an arm serving as a handle and another arm adapted to have wedging engagement with the door as the lever is rotated.
2. In a furnace, the combination of a door frame, a door loosely mounted on the frame, and means for forcing the door tightly against the frame, including a lever pivoted on the frame and having an arm serving as a handle and another arm adapted to have wedging engagement with the door as the lever is rotated, and means for adjusting the throw of the lever.
3. In a furnace, the combination of a door frame, a door, a double pivot hinge mounting said door on the frame, and means for forcing the door against the door frame, including a lever pivoted on the frame adjacent to the hinged edge of the door and having a long arm serving as a handle, and a short arm having a surface eccentric with respect to its pivot for wedging engagement with the door.
4. In a furnace, the combination of a door

frame, a door mounted to swing and to move bodily relative to said frame, and a lever pivoted to the frame, having a long arm serving as a handle and a short arm adapted to have wedging engagement with the door to force it against the frame.

5. In a furnace, the combination of a door frame, a door loosely mounted on the door frame, and a lever pivoted on the frame and having a short arm presenting a surface eccentric with respect to its pivot for wedging engagement with the door.

6. In a furnace, the combination of a door frame, a door loosely mounted on the door frame, a lever pivoted on the frame and having a short arm presenting a surface eccentric with respect to its pivot for wedging engagement with the door, and an eccentric bushing adjustably mounted in said lever.

7. In a furnace, the combination of a door frame, a door loosely hinged at one edge to said frame, a head pivoted on the frame to swing into and out of the path of the door, a wedging device carried by the head for forcing the door against the frame, and a second wedging device on the opposite side of said door.

8. In a furnace, the combination of a door frame, a door loosely hinged at one edge to said frame by a double pivot hinge, a head pivoted on the frame to swing into and out of the path of the door, a screw in the head adapted to engage the door, and a lever adapted to coact with said screw to hold said door in contact with said frame.

9. In a furnace, the combination of a door loosely hinged on the frame, a lever pivoted on the frame adjacent to the hinge and having a short arm for engagement with the door, a head pivoted on the frame opposite to the hinge, to swing in front of the door, and a screw in the head for engagement with the door.

FERD ELIEL WERTHEIM.
